B. SKIDMORE, JR

TANK OR LIQUID RECEIVER

Filed July 20, 1922

FIG. 2

FIG. 1

INVENTOR:
Benjamin Skidmore Jr.

BY: *Benjamin Skidmore Jr.*
Attorney.

UNITED STATES PATENT OFFICE.

BENJAMIN SKIDMORE, JR., OF CHICAGO, ILLINOIS.

TANK OR LIQUID RECEIVER.

Application filed July 20, 1922. Serial No. 576,201.

To all whom it may concern:

Be it known that I, BENJAMIN SKIDMORE, Jr., a citizen of the United States, residing at Chicago, in the county of Cook and State 5 of Illinois, have invented certain new and useful Improvements in Tanks or Liquid Receivers, of which the following is a specification.

This invention relates to improvements in 10 pivotally mounted tanks or liquid receivers particularly adapted, though not necessarily limited in its use, with steam heating systems and which tank communicates with the return pipe of the system and is adapted to 15 receive air and water of condensation, the liquid being removed from the tank by means of suitable pumping apparatus, the operation of which latter is controlled by the oscillation or pivotal movement of the 20 tank and which movement of the tank is in turn controlled by the height or accumulation of the liquid therein.

Heretofore in apparatus of this character the construction of the pivot joint has been 25 quite a desideratum as the water of condensation has usually been passed therethrough from the system to the tank, with the result that care was necessary to provide a fluid tight joint. Such joints are more or less 30 expensive and require considerable attention and frequent adjustments and repacking.

To overcome these difficulties and objections and to provide an improved, simple, durable, compact and comparatively cheap 35 construction of joint or connection between the pivotally mounted tank and the return line of the system, thereby obviating the necessity of conducting the liquid through the pivotal support of the tank, is one of the objects of the present invention.

To the attainment of these ends and the accomplishment of other new and useful objects as will appear, the invention consists 40 in the features of novelty in substantially 45 the construction, combination and arrangement of the several parts hereinafter more fully described and claimed and shown in the accompanying drawing illustrating this invention and in which—

Figure 1 is a vertical, longitudinal sectional view of a tank constructed in accordance with the principles of this invention.

Figure 2 is a vertical sectional view as taken on line 2—2, Figure 1.

Referring more particularly to the drawing the numeral 10 designates a supporting

base of any desired size and configuration arranged above which base are spaced uprights or standards 11, having bearing openings 12 adjacent the upper ends thereof. 60

A closed tank or liquid receiver 13 is pivotally mounted upon the standards 12 by means of suitable trunnions 14 connected with the tank to one side of the longitudinal center thereof. The tank is provided with 65 an opening 15 in the bottom thereof, and which opening constitutes an inlet and an outlet for the fluid, permitting the fluid to flow into and out of the tank.

Supported upon the base 10 and beneath 70 the tank is a chamber 16 having an opening 17 in the top thereof, and which opening is arranged in alinement with the opening 15 in the tank 13. The tank 13 may be spaced for any desired distance above the top of 75 the chamber 16 and interposed between the tank and the chamber is a bellows-like pipe 18, constructed of any suitable material. The diameter of the pipe 18 is substantially 80 equal to the diameters of the openings 15 and 17 and forms a communication between the chamber 16 and the tank 13. One end of the pipe 18 is secured to the tank 13 preferably by means of a flange 19 which abuts 85 a bearing surface 20, preferably connected with the trunnions 14 and a clamping element 21 also engages the flange 19. The clamping element 21 is secured in position 90 by suitable devices 22 such as screws, bolts, or the like.

The other end of the pipe 18 is provided with a flange 23, which rests against a surface 24 connected with the chamber 16 and a clamping element or ring 25 co-operates 95 with the surface 24 to clamp the flange 23 of the pipe 18 therebetween. The element 25 may be secured in position by means of any suitable fastening devices such as bolts 26.

The bellows, or pipe 18 is of any desired 100 flexibility such as will permit the oscillation of the tank 13 about its pivot 14 without interfering with the free oscillation of the tank.

If desired, a stop 27 may be disposed on 105 one side of the pivot of the tank for arresting its movement in one direction and this stop 27 may be provided with a suitable cushioning device 28. An elastic element 29 such as a coil spring or the like is secured 110 to a suitable support 30 and tends normally to move the tank 13 in a direction

about its pivot to return it to its normal position, but when the accumulation of the liquid in the tank is sufficient to cause the same to swing about its pivot in one direction, the elastic element will be compressed and energy will be stored therein, which energy will return the tank to its normal or horizontal position when the liquid is removed therefrom.

10 The chamber 16 is provided with an inlet opening 31 which is connected with the return pipe of the heating system and is provided with an outlet 32 for removing the liquid or water of condensation from the 15 system and also from the tank 13 and chamber 16. This may be accomplished in any suitable manner such as by means of a pump device 33 connected with any suitable source of power through the medium of a shaft 20 34 and coupling 35.

15 The pumping apparatus is electrically controlled in any desired or suitable manner and the electric control is itself controlled by the height of the liquid in the tank 13. 25 To that end there may be provided separable contact terminals 36—37, one of which, the contact 37, is connected with the tank and is movable into and out of operative relation with respect to the contact 36 by the 30 oscillation of the tank. The tank may, if desired, be provided with a vent opening controlled by means of a suitable cock 38.

35 While in the present exemplification of the invention there is shown and described a chamber 16 disposed intermediate the return pipe and the bellows-like pipe 18, it is to be understood that this chamber may be of any desired size and configuration or may be in the form of any suitable connection 40 between the two.

45 In operation, and when the tank is empty it will assume the position as shown in full lines in Figure 1. As the water of condensation from the return line accumulates in the chamber 16, it will flow into the tank, when such accumulation is great enough, through the bellows 18. The tank 13 will remain in the position shown in full lines in Figure 1 until the accumulation of the 50 water of condensation therein is sufficient to cause the tank to swing about its pivot 14 into the dotted line position shown in Figure 1. This movement of the tank will cause the contact terminal 37 to engage and co-operate with the contact terminal 36 to complete the circuit and start the pumping apparatus into operation to withdraw or discharge all of the liquid of condensation from the tank and from the chamber 16. 55 The liquid of condensation will flow both into and out of the tank through the bellows 18.

60 As soon as the liquid has been removed from the tank the energy which has been stored in the elastic member 29 during the

descending movement of the tank will operate upon the tank to move it back about its pivot into the full line position and at the same time the contact terminals 36 and 37 will be separated.

70 During the oscillation or movement of the tank 13 about its pivot 14 the bellows 18 will yield sufficiently so as not to interfere with the free movement of the tank.

75 It will be manifest that inasmuch as the bellows 18 is located in close proximity to the pivot 14, the bellows will be subjected to only a slight degree of movement during the oscillation of the tank, and this is particularly advantageous when the bellows is so constructed of metal.

What is claimed as new is:—

1. In combination, a tilting receiving chamber controlled in its movement by the accumulation of liquid therein, a combined inlet and outlet for liquid adjacent but separate from the pivot of the chamber, and means connecting said inlet and outlet with the return line of a steam heating system, the said means embodying a flexible pipe section.

85 2. In combination, a tilting receiving chamber controlled in its movement by the accumulation of liquid therein and removal of the liquid therefrom, a combined inlet and outlet for liquid, and means adjacent but 90 separate from the pivot and connecting said inlet and outlet with the return line of a steam heating system, the said means embodying a bellows pipe section.

95 3. An apparatus of the character described embodying a receiving chamber, means pivotally supporting the said chamber, said chamber having an opening through one wall thereof independent of the pivot of the 100 chamber, a liquid passage terminating short of the said opening, and a bellows pipe section connected with the said chamber and the end of the said passage and forming a communication between the said passage and the said opening.

105 4. An apparatus of the character described embodying a receiving chamber, means pivotally supporting the said chamber, said chamber having an opening through one wall thereof independent of the pivot of the chamber, a liquid passage terminating short of the said opening, and a bellows pipe section connected with the said chamber and the end of the said passage and forming a communication between the said passage and the said opening, the said bellows constituting an inlet and an outlet for the liquid to and from the chamber.

115 5. An apparatus of the character described embodying a receiving chamber, means pivotally supporting the said chamber, said chamber having an opening through one wall thereof independent of the pivot of the chamber, a liquid passage terminating short 120 of the said opening, and a bellows pipe section connected with the said chamber and the end of the said passage and forming a communication between the said passage and the said opening, the said bellows constituting an inlet and an outlet for the liquid to and from the chamber.

125 6. An apparatus of the character described embodying a receiving chamber, means pivotally supporting the said chamber, said chamber having an opening through one wall thereof independent of the pivot of the chamber, a liquid passage terminating short 130 of the said opening, and a bellows pipe section connected with the said chamber and the end of the said passage and forming a communication between the said passage and the said opening, the said bellows constituting an inlet and an outlet for the liquid to and from the chamber.

of the said opening, a bellows pipe section connected with the said chamber and the end of the said passage and forming a communication between the said passage and 5 the said opening, the said bellows constituting an inlet and an outlet for the liquid to and from the chamber, and means for conveying away the liquid.

6. An apparatus of the character described 10 embodying a receiving chamber, means pivotally supporting the said chamber, said chamber having an opening through one wall thereof independent of the pivot of the chamber, a liquid passage terminating short 15 of the said opening, a bellows pipe section connected with the said chamber and the end of the said passage and forming a communication between the said passage and the said opening, pumping mechanism for conveying away the liquid from the chamber, 20 and means controlled by the tilting action of the chamber for controlling the said pumping mechanism.

7. An apparatus of the character described 25 embodying a receiving chamber, means pivotally supporting the said chamber, said chamber having an opening through one wall thereof independent of the pivot of the chamber, a liquid passage terminating short 30 of the said opening, a bellows pipe section connected with the said chamber and the end of the said passage and forming a communication between the said passage and the said opening, pumping mechanism for 35 conveying the liquid away from the chamber.

ber, and electric means controlled by the height of the liquid in the chamber for controlling the pumping mechanism.

8. In combination, a tilting receiving chamber supported at one side of the center 40 of gravity, in combination with an inlet and an outlet for fluid disposed in close proximity to but separate from the pivot of the chamber, and means connecting said inlet and outlet with the return line of a steam 45 heating system, the said means embodying a flexible pipe section.

9. In combination, a tilting receiving chamber supported at one side of the center 50 of gravity, in combination with an inlet and an outlet for fluid disposed in close proximity to but separate from the pivot of the chamber, and means connecting said inlet and outlet with the return line of a steam 55 heating system, the said means embodying a bellows pipe section.

10. An apparatus of the character described embodying a pivotally mounted receiving chamber having an opening constituting an inlet and an outlet for fluid and 60 disposed in close proximity to but separate from the pivot, a fluid passage terminating short of said opening, and a bellows pipe section forming a connection between the end of said passage and the said opening. 65

In testimony whereof I have signed my name to this specification, on this 17th day of July, A. D. 1922.

BENJAMIN SKIDMORE, JR.
